Application December 12, 1945, Serial No. 634,516

3 Claims. (Cl. 250—27)

1

This invention relates to sawtooth wave generators and more particularly to a combination of a multivibrator and resistor-capacitor network that provides synchronously and independently a sawtooth wave and positive and negative gates.

Gate producing multivibrators and many types of sawtooth generators are well known in the art. However separate circuits are needed for each purpose as well as additional circuits for achieving synchronism between gates and sawtooth.

The present invention provides in a single integrated circuit a greatly simplified means of furnishing synchronous gates and a sawtooth wave.

An object of this invention is to provide in one simple circuit a combination gate and sawtooth wave generator.

Another object is to control the cyclical frequency of the gate and sawtooth wave generator by means of synchronizing triggers.

Another object is to employ a multivibrator as the device for controlling the charge and discharge of a resistor-capacitor network to produce a saw-tooth wave.

These and other objects and features of this invention will become apparent upon a consideration of the following detailed description when taken together with the accompanying drawings, the figures of which illustrate a typical embodiment of this invention.

Fig. 1 is a circuit diagram of the multivibrator with the associated resistor-capacitor network for the sawtooth output.

Fig. 2 illustrates the waveforms at various points of the circuit of Figure 1 in their proper phase relationships.

In Fig. 1, tubes 10 and 11 are the two stages of a multivibrator. Positive potential at point 12 is supplied to the plate of tube 10 through resistor 16 and to the plate of tube 11 through resistor 17. The control grid of tube 11 is biased from 12 through resistors 18 and 19 in series. The control grid of tube 10 is biased through resistor 20 which connects to the sliding arm 21 of resistor 22, which is in series with resistor 23 between point 12 and ground. Capacitor 26 connects the grid of 10 to the plate of 11. Capacitor 27 connects the plate of the tube 10 to the junction of resistors 18 and 19. Resistor 28 connects between the cathode of the tube 11 and ground and is the cathode output circuit. The cathode of tube 10 is tied to ground through resistor 29. Resistor 30, capacitor 31 and resistor 32 are in series across resistor 29, and resistor 33 connects between the junction of 31 and 32 and point 34 at which synchronizing triggers 39 are introduced. Resistors 32 and 33 provide voltage division to adjust the synchronizing triggers 39 to the desired value.

Resistor 36 and capacitor 37 are in series be-

2

tween the plate of tube 10 and ground and provide the sawtooth output voltage 41 at point 38.

In Fig. 2 the negative triggers 39 are those applied at 34 to the cathode circuit of tube 10. Voltage wave form 40 appears at the grid of tube 10. Wave form 41 is that of the sawtooth output voltage at point 38. Voltage wave form 42 appears at the grid of tube 11.

The natural frequency of the multivibrator is chiefly controlled by the time constant of the capacitor 27 and the resistor 18, which is large compared to resistor 19, by the time constant of the capacitor 26 and the resistor 20, by the voltage appearing at the top end of resistor 18, and by the voltage appearing at the slider arm 21. The capacitor 27 and resistor 18 control the time constant of the grid of tube 11 and thus the time tube 11 is nonconducting. The capacitor 26 and resistor 20 as well as the voltage at 21 control the time constant of the grid of tube 10 and thus control the time tube 10 is non-conducting.

Negative and positive gates in phase opposition appear at the plate and cathode of tube 11 respectively during the conducting period of tube 11, the negative gate being opposed in phase to wave form 42 at the grid of tube 11 and the positive gate being in phase with wave form 42.

When tube 11 starts to conduct, tube 10 is cut off and capacitor 37 is charged towards the potential at 12 through resistors 16 and 36 in series. This forms the upward sweep of sawtooth output voltage wave form 41. When the multivibrator reverses, tube 11 cuts off as shown in the negative pulse of wave 42, ending the positive and negative gates. Tube 10 begins to conduct and forms a low resistance discharge path for capacitor 37 in series with resistors 36 and 29. The voltage on capacitor 37 then sweeps downward relatively rapidly compared to the voltage rise on charging through the large resistor 16. Thus the sawtooth output voltage wave form 41 is formed sweeping upward synchronously with the positive and negative gates from tube 11 and returning rapidly to the starting point when the gates cease. It will be noted that when tube 10 conducts it effectively receives its plate potential from capacitor 37 and resistor 36 acts as the plate resistor. Capacitor 37 and resistor 36 are such in value that the voltage supplied to the plate of tube 10 varies but 10 percent.

The cyclical frequency of the multivibrator can be synchronized to the frequency of the synchronizing triggers 39 or sub-multiples thereof, when the time that the grid of tube 10 is cut off is greater than the period of the synchronizing triggers. Frequency division results from the fact that the grid of tube 10 is driven so far negative as shown in 40 that the negative triggers 39 on the cathode of 10 are insufficient to make the tube conduct. By adjusting the voltage at 21, the cut off time of the grid of tube 10 can be

varied so that, for instance, the grid is still far below cut off when the second negative trigger arrives but is almost back to cut off when the third negative trigger arrives, causing the tube to fire and trip the multivibrator. The voltage at 21 and the grid circuit time constant can be adjusted so that tube 10 fires on the first, second or subsequent triggers to provide a cyclical frequency of the multivibrator which is equal to or a sub-multiple of the synchronizing frequency.

Although there is shown and described only a certain specific embodiment of multivibrator sawtooth generator, the many modifications possible thereof will be readily apparent to those familiar with the art. Therefore this invention is not to be limited except insofar as is necessitated by the prior art and the spirit of the appended claims.

What is claimed is:

1. A circuit for the synchronous generation of a sawtooth voltage wave with positive and negative voltage square waves comprising, a multivibrator including first and second electron tubes, each of said tubes having a cathode, an anode and a control grid, means for coupling the anode of each of said tubes to the control grid of the other tube, a source of potential to energize said multivibrator, anode and cathode resistors for connecting each of said tubes individually to said potential source, means for connecting the control grid of said first tube to said potential source to bias said first tube to be normally conducting, means for connecting the control grid of said second tube to said potential source to bias said second tube to be normally nonconducting, a storage capacitor and a series resistor connected to shunt said second tube between the anode of said second tube and the end of the cathode resistor of said tube remote the cathode thereof, a source of synchronizing pulses having a predetermined repetition rate, means for applying pulses from said source to bias said second tube to conduction thereby terminating the conduction of said first tube for a time interval determined by the time constant of the grid circuit of said first tube, whereby said storage capacitor charges relatively slowly from said potential source during nonconduction of said second tube and discharges relatively rapidly during conduction of said second tube while termination of conduction of said first tube terminates a negative voltage square wave at the anode thereof and a positive voltage square wave at the cathode thereof.

2. A circuit for the synchronous generation of a sawtooth voltage wave with positive and negative voltage square waves comprising, a multivibrator including first and second electron tubes, each of said tubes having a cathode, an anode and a control grid, means for coupling the anode of each of said tubes to the control grid of the other tube, a source of potential to energize said multivibrator, anode and cathode resistors for connecting each of said tubes individually to said potential source, means for connecting the control grid of said first tube to said potential source to bias said first tube to be normally conducting, means for connecting the control grid of said second tube to said potential source to bias said second tube to be normally nonconducting, a storage capacitor and a series resistor connected to shunt said second tube between the anode of said second tube and the end of the cathode resistor of said tube remote the cathode

thereof, a source of synchronizing pulses having a predetermined repetition rate, the grid circuit of said second tube having a time constant to provide a multivibrator frequency at the frequency of said synchronizing pulses, means for applying pulses from said source to bias said second tube to conduction thereby terminating the conduction of said first tube for a time interval determined by the time constant of the grid circuit of said first tube, whereby said storage capacitor charges relatively slowly from said potential source during nonconduction of said second tube and discharges relatively rapidly during conduction of said second tube while termination of conduction of said first tube terminates a negative voltage square wave at the anode thereof and a positive square wave at the cathode thereof.

3. A circuit for the synchronous generation of a sawtooth voltage wave with positive and negative voltage square waves comprising, a multivibrator including first and second electron tubes, each of said tubes having a cathode, an anode and a control grid, means for coupling the anode of each of said tubes to the control grid of the other tube, a source of potential to energize said multivibrator, anode and cathode resistors for connecting each of said tubes individually to said potential source, means for connecting the control grid of said first tube to said potential source to bias said first tube to be normally conducting, means for connecting the control grid of said second tube to said potential source to bias said second tube to be normally nonconducting, a storage capacitor and a series resistor connected to shunt said second tube between the anode of said second tube and the end of the cathode resistor of said tube remote the cathode thereof, a source of synchronizing pulses having a predetermined repetition rate, means to adjust the bias of said second tube to provide a multivibrator frequency at a predetermined submultiple of the frequency of said synchronizing pulses, means for applying pulses from said source to bias said second tube to conduction thereby terminating the conduction of said first tube for a time interval determined by the time constant of the grid circuit of said first tube, whereby said storage capacitor charges relatively slowly from said potential source during nonconduction of said second tube and discharges relatively rapidly during conduction of said second tube while termination of conduction of said first tube terminates a negative voltage square wave at the anode thereof and a positive voltage square wave at the cathode thereof.
